[57] CLAIM

The ornamental design for a dispensing nozzle, as shown.

DESCRIPTION

FIG. 1 is a perspective view taken from the top, front and left side of a dispensing nozzle showing our new design;

FIG. 2 is a top plan view thereof, the bottom being a mirror image of the top shown;

FIG. 3 is a left side elevational view thereof, the right side being a mirror image of the left side shown;

FIG. 4 is a front elevational view thereof; and

FIG. 5 is a rear elevational view thereof.

FIG.1

FIG.2

FIG.3
